Elgin, Ill., assignors to McGraw Electric Com-
pany, Elgin, Ill., a corporation of Delaware

Application May 28, 1947, Serial No. 139,335

Term of patent 14 years

(Cl. D49—6)

To all whom it may concern:

Be it known that we, Max McGraw and Anne E. Cosgrove, citizens of the United States, Max McGraw residing in Chicago, county of Cook, State of Illinois, and Anne E. Cosgrove residing in Elgin, county of Kane, State of Illinois, have invented a new, original, and ornamental Design for an Electric Iron, of which the following is a specification, reference being had to the accompanying drawings, forming a part thereof, in which

Fig. 1 is a perspective view of an electric iron, showing our new design;

Fig. 2 is a top plan view thereof; and

Fig. 3 is a side elevation.

Figs. 2 and 3 are shown on a reduced scale.

We claim:

The ornamental design for an electric iron, substantially as shown.

MAX McGRAW.
ANNE E. COSGROVE.
